[57] **CLAIM**

The ornamental design for a tool for inserting cables into conduits or the like, substantially as shown.

DESCRIPTION

FIG. 1 is a perspective view of a tool for inserting cables into conduits or the like embodying our new design;

FIG. 2 is an enlarged top plan view thereof;

FIG. 3 is an enlarged front elevational view thereof;

FIG. 4 is an enlarged bottom plan view thereof;

FIG. 5 is an enlarged left end elevational view thereof; and

FIG. 6 is an enlarged right end elevational view thereof.

UNITED STATES PATENT AND TRADEMARK OFFICE
CERTIFICATE OF CORRECTION

PATENT NO. : DES. 289,132

DATED : April 7, 1987

INVENTOR(S) : Curtis M. Wright and Charles Wray

It is certified that error appears in the above-identified patent and that said Letters Patent are hereby corrected as shown below:

Line [21], delete "834,142" and insert --634,142--.

Signed and Sealed this
First Day of September, 1987

Attest:

DONALD J. QUIGG

Attesting Officer

Commissioner of Patents and Trademarks
